ABSTRACT: An educational game having a playing board with a circular path divided into equal radial segments between a start area and a finish area. A plurality of indicator cards having various lengths of measuring indicia are positionable on the board adjacent the path for measuring a distance along the path. The distance is recorded by placing a token in one of the segments. A selector operated by the player is used to indicate one of the cards.

MEASURING GAME APPARATUS

BACKGROUND OF INVENTION

Educational games utilizing a playing board having an elongated path have been used in combination with playing pieces and question cards to advance the playing pieces along the path. U.S. Pat. No. 1,635,734 shows this type of game with question cards wherein the correct answers to questions on the cards determine the number of spaces that the token is moved. In other words games, indicators, as dice, are used to determine the number of stations that a player shall move his token along a separate path having consecutively numbered stations. An example of this game is shown in U.S. Pat. No. 1,707,323.

SUMMARY OF INVENTION

The invention relates to a competitive educational game which utilizes a playing board having a path connecting a starting area with a finish area. A plurality of measuring means are used to measure various distances along the path. A token or similar movable member is used to record the measured distance on the path. A selector coordinated with the plurality of measuring means is operable by the player to indicate which of the measuring means shall be used to measure the distance along the path. The measuring means indicate distances both in a forward direction and in a rearward direction.

An object of the invention is to provide a competitive game primarily for preschool children which is simple enough so that they can play it without adult supervision. Another object of the invention is to provide a game which can be played without the ability to count while at the same time providing a means whereby the player can learn to count and recognize the appearances of numbers. A further object of the invention is to provide a game wherein the player is taught distance perception in both a forward direction and a rearward direction.

In the drawings:

FIG. 1 is a fragmentary plan view of a game board of the invention showing the elongated path connecting START with FINISH;

FIG. 2 is a plan view of the spinner;

FIG. 3 is a plan view of one indicator card with numbers progressing in a forward direction;

FIG. 4 is a plan view of an indicator card similar to FIG. 3 showing the numbers progressing in a backward direction;

FIG. 5 is a plan view of a second shaped indicator card showing numbers progressing in a forward direction;

FIG. 6 is a plan view of an indicator card similar to FIG. 5 showing the numbers progressing in a backward direction;

FIG. 7 is a plan view of a third form of an indicator card having numbers progressing in a forward direction; and

FIG. 8 is a plan view of an indicator card similar to FIG. 7 having numbers progressing in a backward direction.

Referring to the drawing, there is shown in FIG. 1 an educational game indicated generally at 10 comprising a generally flat board 11 having printed thereon an elongated track or path 12 commencing at a start area or location 13 and terminating at a finish or end area 14. A pictorial representation 16 of a home is located on the board adjacent the start area. A pictorial representation 17 of a school is located on the board adjacent the finish area 14. The elongated path 12 has concentric circular lines extending from the start area or START 13 to the finish area or FINISH 14. The space between the lines is divided into a series of consecutively arranged radial segments 18. Each segment 18 is an individual station or space along the path 12. The segments 18 subdivide the entire path into equal area spaces or stations from the start area 13 to the finish area 14.

Board 11 is flat and made of substantially rigid material, as paper, cardboard, plastic, sheet metal and the like. Various bright designs and figures may be printed on the board in the spaces not occupied by the path. As an example, the board 11

5 may have an overall rectangular shape. Printed on one side of the board is the path 12 having a circular configuration. The inside line of the circle has a radius of 7 1/2 inches and the width of the path is 2 inches. The segments 18 are formed by 4° spaced radial lines so that all the segments have an equal circumferential width. Other dimensions and configurations of the path compatible with the method of playing the game can be used.

10 Referring to FIGS. 3 to 8, there are shown indicator or measuring cards indicated generally at 21 to 26 and used as separate measuring means positionable on the board adjacent the path for measuring distances along the path. A first indicator card 21 has an arcuate outer edge 29 which coincides with the curvature of the inside curved line of the path. The peripheral portion of the card adjacent the edge 29 is divided into an equal number of radial spaces 31 which are consecutively numerically numbered between a beginning arrow mark 32 and an end arrow mark 33. Each mark has a 15 different color and an arrowhead terminating at the arcuate edge 29. A directional arrow 34 pointing in a forward direction connects the marks 32 and 33. Eight spaces separate the beginning arrow mark 32 and end arrow mark 33.

20 Indicator card 22 has an identical shape as the card 21, including an arcuate edge 36. The peripheral portion of the card adjacent the edge 36 is subdivided into a number of circumferential spaces 37. The spaces are numerically numbered between a beginning arrow mark 38 and an end arrow mark 39. A directional arrow 40 extended in a 25 backward or rearward direction connects the beginning mark with the end mark 39. Five spaces separate the beginning mark 38 and end mark 39. In both indicator cards 21 and 22, the spaces 31 and 37 have a width equal to the width of the segments 18 of the path so that the numbers on the cards also 30 indicate a number of spaces on the path. Cards 21 and 22 are indicated as being yellow in color.

35 FIGS. 5 and 6 show pie-shaped second indicator cards 23 and 24 for measuring a distance along the path 12. These cards are blue to distinguish them from cards 21 and 22. Card 40 23 has an outer arcuate edge 41 similar to edge 29 of card 21. The peripheral portion of the card adjacent edge 41 is subdivided into a number of circumferential spaces. A selected number of spaces carry numbers located between a 45 beginning arrow mark 43 and an end arrow mark 44. A directional arrow 45 connects the beginning mark 43 with the end mark 44. Card 24 has a similar arcuate edge 46 and a peripheral portion divided into circumferential spaces 47. The spaces 47 between a beginning arrow mark 48 and an end arrow mark 49 are consecutively numbered. A rearward 50 directional arrow 51 connects the beginning mark 48 with the end mark 49.

55 Third shaped indicator cards 25 and 26, shown in FIGS. 7 and 8, also carry indicia to indicate a distance along the path. The cards are red. Card 25 has an outer arcuate edge 52 located adjacent a circumferential portion which is circumferentially divided into spaces 53. A plurality of spaces are numbered between a beginning arrow mark 54 and an end arrow mark 55. A forward directional arrow 56 connects the marks 54 and 55. Card 26 has an arcuate edge 57 forming the outer edge of an arcuate portion or band divided into a 60 number of circumferential spaces 58. The first space on the right side of the card is identified with a beginning arrow mark 59. Circumferentially spaced from the beginning mark is an end arrow mark 60. The spaces between the beginning mark and the forward border line of the end mark space are 65 identified with consecutive numbers 1 and 2. The marks are connected with a rearward directional arrow 61.

70 All of the indicator cards have arcuate outer edges which have curvatures which coincide with the curvature of the inside edge of the path 12. This outer edge forms the outside lines of peripheral arcuate portions of the cards which are circumferentially divided into a number of spaces. The width of each space is equal to the width of the space 18 of the path 12. The spaces are consecutively numbered from either the 75

right side or the left side. The indicator cards 21-26 are generally flat members made of substantially rigid material, as wood, metal, cardboard, paper and the like. The lines, arrow marks and numbers are printed on only one face of each card. The opposite face of the card does not provide measuring information.

In a preferred embodiment of the game, the indicator cards 21, 23 and 25 are forward cards in that the directional arrows are located in a forward or clockwise direction. The measurement indicated by these cards may be in amounts of one, three, five, seven, eight, nine or 10 spaces. The indicator cards 22, 24 and 26 are backward cards as the directional arrows 40, 51 and 61 are pointed in a backward or counterclockwise direction and extend in amounts of two, four or six spaces.

The measuring lengths indicated by the spaces on the several indicator cards may vary, with some cards having the same numbered spaces. Also, the colors of the cards may be changed and the shapes of the cards may be altered around the design of the arcuate outer edge which is correlated with the shape of a portion of the path 12.

Referring to FIG. 2, there is shown the selector operable to indicate one of the measuring or indicator cards used to measure a distance along the path 12. The selector indicated generally at 62 is a spinner comprising a circular disc 63 divided into three 120° sectors 64, 65 and 66. Positioned over the disc 63 is a rotatable spinner needle or pointer 67 having a point 68. A pivot member 69, as a rivet or grommet, rotatably connects the spinner needle to the center of the disc 63. Located in sectors 64, 65 and 66 are outlines 71, 72 and 73 which correspond to the shapes and colors of the indicator cards 21, 23 and 25, respectively. The card outlines and colors on the disc 63 provide the players with visual association between selector 62 and the indicator cards 21-26. The corresponding colors are indicated on the selector so that the player can use either the shape outline or the color code to determine the selected indicator card. In this manner, both color recognition and object shape recognition are used by the player to transmit the color and shape information determined by the selector 62 to the correspondingly color and shaped indicator card.

In use, initially indicator cards 21 and 22 are intermixed and placed face down in a first pile. The indicator cards 23 and 24 are placed in a second pile and the indicator cards 25 and 26 are placed in a third pile. While the number of cards in each pile may be varied, the preferred number is 7 forwardly directed cards and three rearwardly directed cards. There are a total of ten cards in each pile.

The players can take turns in spinning the pointer 67 on the selector 62. To determine the first move, all of the players spin the pointer 67. The player that ends on the red begins. If two or more players select red, there is a playoff until only one has the red. The first player spins the pointer 67 and takes an indicating card corresponding to the color or shape determined by the location of point 68. As shown in broken lines in FIG. 2, pointer 67 has selected a yellow card. If the pointer stops on a line, another turn is taken by the player. The indicator card 21 selected by the pointer is lined up with its outside edge 29 in alignment with the inside line of the path 12 on the playing board. The beginning mark 32 is lined up with the START position and the player's token 74 is moved in the direction of the arrow 34 to the space 18A opposite the indicating card's end mark 33. Token 74 is moved nine spaces forward in the path 12 as directed by the measuring indicia on card 21.

On the next move of the same player, the pointer 67, shown in full lines in FIG. 2, has stopped on segment 65 indicating

the indicator card 23. This card is placed on the game board with the arcuate edge 41 aligned with the inside edge of the path 12. The beginning mark 43 is placed adjacent the segment 18A having token 74. This locates the ending mark 44 adjacent a new segment or station 18B. The token 74 is moved from station 18A to station 18B.

If the indicator card selected had a reverse or backward direction, the token would be moved backward the indicated number of spaces. Each player has a token. All the players of 10 the game take successive turns moving their tokens forward or backward as their selected measuring cards indicate. The first player that reaches FINISH 14 first is the winner.

After each indicator card is used, it is placed on the bottom of its respective pile. If a player selects an indicator card that 15 has a backward measurement on his first try, the token is not moved. The player's turn is lost. The players token may not be reversed past the beginning area or START 13.

The size and dimensions of the game as well as the shape of 20 the path will be determined by how large a unit is desired. Magnetic tokens can be used with a metal board. The tokens 25 can be shaped to represent small cars, bikes, doll buggies, ships, planes or other units of transportation.

I claim:

1. A game apparatus comprising: a playing board having a 25 start area, a finish area and a continuous path connecting the start area with the finish area, a plurality of distance-measuring means, each measuring means having means to indicate a distance, at least one of said measuring means indicating a distance different from the indicated distance on the remainder of the measuring means, each measuring means positionable on the board for measuring a distance along the path, at least one token, and selector means operable to indicate by chance one of the measuring means, said one measuring means usable to measure a distance along the path 30 which is marked by placing the token in the path.

2. The game apparatus of claim 1 including: lines separating the path into stations, said means on the measuring means corresponding to the lines separating the path, whereby the measuring means is used to indicate a number of stations in 35 the path.

3. The game apparatus of claim 2 wherein the path is circular and said lines separate the path into arcuate segments.

4. The game apparatus of claim 3 including numbers on the 40 measuring means to indicate the measured number of arcuate segments in the path.

5. The game apparatus of claim 3 wherein each measuring means has an arcuate edge corresponding to the curvature of the circular path and said means on said measuring means are radial lines defining arcuate segments along said edge 45 corresponding in size to the arcuate segments of the path.

6. The game apparatus of claim 5 including a beginning mark and an end mark on the measuring means, the segments between the marks being consecutively numbered.

7. The game apparatus of claim 5 including a beginning 50 mark and an end mark on spaced segments and a directional arrow connecting the marks.

8. The game apparatus of claim 7 wherein the directional arrow points in a clockwise direction when the measuring means is correctly positioned adjacent the path.

9. The game apparatus of claim 7 wherein the directional arrow points in a counterclockwise direction when the measuring means is correctly positioned adjacent the path.

10. The game apparatus of claim 1 wherein part of the 55 measuring means have means designating movement a forward distance along the path and the other part of the measuring means have means designating movement a backward distance along the path.
